UNITED STATES PATENT OFFICE.

WILHELM VOGT, OF PHILADELPHIA, PENNSYLVANIA, ASSIGNOR TO
ABRAHAM A. LANDIS, OF COLLEGEVILLE, PENNSYLVANIA.

GRIPPING MECHANISM FOR CARS.

SPECIFICATION forming part of Letters Patent No. 571,812, dated November 24, 1896.

Application filed March 5, 1896. Serial No. 581,879. (No model.)

To all whom it may concern:

Be it known that I, WILHELM VOGT, a subject of the Emperor of Germany, residing at the city of Philadelphia, in the county of Philadelphia and State of Pennsylvania, have invented certain new and useful Improvements in Gripping Mechanism for Cars of Pleasure-Railways, of which the following is a specification.

10 My invention has relation to mechanism for pleasure-railway cars designed to automatically grip the car or cars while moving to a moving rope or cable at such a time when the speeds of car and cable are substantially 15 equal, whereby the jolting and jarring of the car heretofore incidental to the connection of the same with the cable is avoided; and in such connection it relates particularly to the construction and arrangement of such a gripping mechanism.

The principal objects of my invention are, first, to provide a simple, efficient, and automatic gripping device for pleasure-railway cars, by means of which the cars while in motion for the purpose of hauling or shifting may be secured to a moving cable only when the speed of the car has become reduced to the speed of the cable; second, to provide a gripping mechanism consisting, essentially, 30 of two blocks or cheeks designed to grip the cable and having a range of longitudinal movement in a block secured to the car, each of said cheeks being secured to one end of a longitudinally-movable rod, the other end of which carries two spring-controlled pivoted jaws, between which the cable is adapted to slide, and when the speed of the cable is equal to that of the car carrying the grip said jaws are adapted to be actuated by said cable to 35 move the gripping-blocks into positive engagement with the cable, and, third, to provide in such a gripping mechanism two ratchet-controlled friction-rolls carried by the spring-jaws adapted to rotate loosely upon the cable when the car is moving faster than the cable, but adapted to be locked against movement when the cable approximates in speed that of the car.

My invention, stated in general terms, consists of a grip mechanism for pleasure-railway

cars constructed and arranged in the manner hereinafter described and claimed.

The nature and scope of my invention will be more fully understood from the following description, taken in connection with the accompanying drawings, forming part hereof, and in which—

Figure 1 is a top or plan view of the gripping device removed from the car, embodying the main features of my invention, and illustrating, in connection therewith, a cable to which said gripping mechanism and car are adapted to be secured. Fig. 2 is an underneath plan view of the gripping device, partly broken away, and illustrating the construction and arrangement of the gripping blocks or cheeks. Fig. 3 is an end view of the pivoted friction-jaws of Fig. 1. Fig. 4 is a cross-section taken on the line $\alpha\alpha$ of Fig. 1. Fig. 5 is a top or plan view of a slightly-modified form of the gripping mechanism illustrated in Fig. 1. Fig. 6 is an underneath plan view of a modified form of the gripping-cheeks illustrated in Fig. 2, and Fig. 7 is a top or plan view of a modified form of the pivoted friction-jaws of Fig. 1.

Referring to the drawings, a represent as frame or block of wood or any other suitable material adapted to be bolted or otherwise secured to the platform or truck of the car (not shown) in such a manner that the same projects downward from the car in the path of a moving cable b . The underside of this block a is recessed, as at a' , to form a wedge-shaped slide or guideway for the two substantially 85 wedge-shaped gripping blocks or cheeks d and d' . These cheeks are confined to the block a by means of bolts d^2 , so arranged that the bolts have a range of movement in slots d^3 , cut in converging directions in the block a , to 90 thereby permit the cheeks d and d' , secured to said bolts, to move slightly in the recess a' back and forth in a longitudinal direction. The cheeks d and d' are provided with gripping-faces, preferably constructed by cutting out one face, as at d^4 , and forming a corresponding projection on the other face, as at d^5 , substantially as illustrated in Fig. 2. When the cheeks d and d' are moved toward the converging end of the recess a' , being guided in 100

their movement by the bolts d^2 , sliding in slots d^3 , the cable b will be firmly pinched or gripped between the recessed face d^4 and the projecting face d^5 . In like manner a reverse movement of the cheeks d and d' will separate the faces d^4 and d^5 and release the cable b therefrom. The cheeks d and d' are moved by the following preferred mechanism: The bolts d^2 , to which the cheeks are secured, are at their upper ends brought into slotted connection with a sliding bar e , which has a range of longitudinal movement in suitable brackets or their equivalents e' , secured to the top of the block a . The bar e projects beyond the block a and, as shown in Figs. 1 to 5, is pivotally connected to two friction-jaws f and f' . These jaws are curved inward, as at f^2 , and then curved outward, as at f^3 , terminating, therefore, in flaring ends. The curved portions f^2 and f^3 project downward in correspondingly-curved wings f^4 , which lie in the path of the cable b . The extreme ends f^3 of the jaws f and f' are connected by a spring f^5 , and the wings f^4 are thereby drawn toward each other to rest frictionally upon the cable b . In the form of friction-jaw shown in Fig. 1 the wings f^4 are cut out at the portions f^6 , corresponding to the portions f^2 of the jaws f and f' , and projecting through each cut-out portion is a friction-roller f^7 , having suitable bearings in the lower part of the wing f^4 , and in the portion f^2 of the jaws f and f' , as clearly illustrated in Fig. 3. These rollers f^7 are permitted to rotate in one direction only, and that the direction opposite to that in which the cable b is moving, and to accomplish this each roller f^7 is provided with a ratchet or ratchet-teeth f^8 at one end, in which rests a pawl or detent f^9 . The detents or pawls f^9 are connected by means of a spring f^{10} , which holds the pawls in engagement with the ratchet-teeth f^8 . In the form shown in Fig. 5 the curved portions of the wings f^4 , corresponding to the portions f^2 of the jaws, rest frictionally upon the cable without the interposition of the rollers.

In Fig. 7, instead of pivoted jaws f and f' of the construction shown in either Figs. 1 or 5, there is secured at the free end of the bar e a fixed slotted extension e^2 , in the slots e^3 of which are placed friction-rolls f^{11} , having a range of sliding movement in said slots, the shafts of the rolls f^{11} being united by means of a spring f^{12} .

In Fig. 6 a modified form of the gripping-cheeks d and d' is shown, in which each cheek consists of an eccentrically-arranged sector lever or cam d^{21} , one arm of which is secured to bolts d^2 , while the other arm carries the cam which is adapted to grip the cable.

In Fig. 5 the bar e is normally shifted in the direction the car is moving by means of a leaf-spring h , bolted or otherwise secured to the block a .

In operation when the car approaches the point where the cable b is to be taken on, and the car is running at a much greater speed

than the cable, the friction-jaws of the gripping mechanism coming in contact with the cable will be pushed toward the right in the drawings, thus opening the gripping-cheeks d and d' or d^{21} and permitting the car to move without engagement with the cable. As the speed of the car gradually slackens the friction of the jaws against the cable will lessen, until finally, when the speed of the car and the cable is the same or approximately the same, the friction-jaws will remain stationary or be drawn slightly to the left by the cable, at which movement the cheeks d , d' , or d^{21} will be drawn by the bar e into gripping position and the car will take on the cable without appreciable resistance or jarring. In the form shown in Fig. 1 the rollers f^7 , when the car is moving faster than the cable, will rotate upon the cable in a direction opposite to that in which the car is moving, but when the cable approximates or slightly exceeds in speed that of the car the rollers f^7 will, by reason of the pawl-and-ratchet arrangement, cease to rotate.

In the form illustrated in Fig. 5 the jaws and bar e will be pushed inward by the cable against the tension of the spring h to open the grip when the car is moving faster than the cable, but said spring h , when the speed of the car and cable is approximately equal, will shift the bar e and grip mechanism in the opposite direction to grip the cable.

To compensate for the vertical swing of the cable when moving, the wings f^4 are made to project a sufficient distance below the block a , and the lateral swing of the cable is compensated for by uniting the friction-jaws with a spring f^5 or f^{12} . The jaws f and f' may each be provided with a lug or stop k , as illustrated in Fig. 1, to prevent the spreading of the same too far apart when the cable is swinging laterally. Upon the rod e is secured a cross-arm m , projecting at right angles to said rod and arranged in the path of a suitable projection (not shown) extending from the floor of the track at the point where the cable is to be cast off. When the projection comes in contact with the arm m , the rod e is shifted to the right to thereby open the gripping-cheeks and release the car from the cable.

Having thus described the nature and objects of my invention, what I claim as new, and desire to secure by Letters Patent, is—

1. In a pleasure-railway car, a gripping mechanism provided with independent friction-jaws adapted to rest upon the cable prior to the gripping thereof, said independent friction-jaws adapted to control the grip mechanism and to prevent the same from operating when the car is moving at substantially greater speed than the cable, as and for the purposes described.

2. A gripping mechanism for pleasure-railway cars, consisting of longitudinally-movable gripping-cheeks adapted to grip the cable, a longitudinally-movable rod secured to

5 said cheeks and adapted to operate the same, and two spring-controlled friction-jaws carried by said rod and adapted to rest frictionally upon the cable, all arranged so that when the car is moving faster than the cable said friction-jaws and rod will be moved in one direction to open the gripping-cheeks and when the car and cable are moving at approximately equal speeds the jaws and rod are moved in an opposite direction to thereby close the gripping-cheeks upon the cable, substantially as and for the purposes described.

10 3. A gripping mechanism for pleasure-railway cars, consisting of two gripping-cheeks, a block supporting said cheeks and recessed to permit of the longitudinal movement thereof, a longitudinally-movable rod sliding on said block and secured at one end to said cheeks, two spring-controlled friction-jaws pivoted to the other end of the rod, and friction-rollers carried by said jaws adapted to rest upon the cable, all arranged so that when the car is moving faster than the cable said rollers will rotate and the jaws and rod will be moved in one direction to open the gripping-cheeks, and when the car and cable are moving at approximately equal speed, the rollers cease to rotate and the jaws and rod are moved in an opposite direction to close the gripping-

15 cheeks upon the cable, substantially as and for the purposes described.

20 4. A gripping mechanism for pleasure-railway cars, consisting of two gripping-cheeks, a block supporting said cheeks and recessed to permit of the longitudinal movement thereof, a longitudinally-movable rod sliding on said block and secured at one end to said cheeks, a leaf-spring adapted to shift said movable rod in one direction on said block, two spring-controlled friction-jaws pivoted to the free end of the rod and adapted to rest upon the cable, all arranged so that when the car is moving faster than the cable, said jaws and rod will be moved against the tension of the leaf-spring to open the gripping-cheeks and when the car and cable are moving at approximately equal speed, the jaws and rod are moved by said leaf-spring to close the gripping-cheeks upon the cable, substantially as and for the purposes described.

25 5. In testimony whereof I have hereunto set my signature in the presence of two subscribing witnesses.

30 WILHELM VOGT.
